UNITED STATES PATENT OFFICE.

JOHN O. KING, OF LOS ANGELES, CALIFORNIA.

HYDROCARBON-BURNER.

1,311,822.

Specification of Letters Patent. Patented July 29, 1919.

Application filed February 13, 1919. Serial No. 276,835.

To all whom it may concern:

Be it known that I, JOHN O. KING, a citizen of the United States, residing at Los Angeles, in the county of Los Angeles and 5 State of California, have invented new and useful Improvements in Hydrocarbon-Burners, of which the following is a specification.

This invention relates to a hydrocarbon burner and particularly pertains to a burner 10 of the type adapted for the combustion of kerosene and especially suitable for use in cook-stoves, ranges, and the like.

It is the object of this invention to provide a burner having a plurality of separate 15 and independent burner elements incorporated in one structure which elements may be employed singly or collectively according to the degree of temperature and location of the flame desired.

20 Another object is to provide a construction in a burner of the above character which will permit ready assemblage of the parts and their easy removal and replacement.

Another object is to provide a form and 25 arrangement of the burner orifices by which over heating of the burner body is obviated.

A further object is to provide a burner 30 for combusting kerosene or similar fuel embodying the Bunsen principle in which means are employed for preventing back fire through the Bunsen.

Other objects will appear hereinafter.

The invention is illustrated in the accompanying drawings, in which;

35 Figure 1 is a perspective view of the burner;

Fig. 2 is a view in longitudinal section and elevation as seen on the line 2—2 of Fig. 4;

40 Fig. 3 is an end elevation as seen in the direction of the arrow 3 in Fig. 2;

Fig. 4 is a view in cross section as seen on the line 4—4 of Fig. 2;

Fig. 5 is a view in cross section as seen on the line 5—5 of Fig. 2.

45 More specifically 10 indicates a base plate which is rectangular in outline and has a longitudinally extending central portion consisting of spaced upwardly incline side walls 11, connected together at their upper edges 50 by a horizontal wall 12, the lower portion of the base plate being formed by side flanges 13, projecting outwardly from the lower edges of the side walls. The base plate is

55 here shown as supported on standards 14 secured to the flanges 13 by stove bolts 15, but may be mounted in any desired manner,

Arranged over the base plate is a burner cap 16 formed with inclined vertically corrugated side walls 17 seating in depressions on the outer portions of the flanges; end walls 18 and 19 connecting the side wall of the burner-cap and extending over the ends of the base plate. Vertical kerfs 20 are cut in the outer portions of the corrugations on the side walls constituting elongated burner 60 openings; the inner portions of the corrugations forming open ended channels between the adjacent kerfs to permit air to pass upwardly over the outer face of the side walls between the burner openings when the 65 burner is in operation to prevent excessive heating thereof. The end portion of the burner-cap adjacent to the end wall 19 is formed with a top platform 21 extending over the elevated wall portion 12 of the base 70 plate and the upper portion of the burner cap between the platform and the end wall 18 is closed by a top wall having a pair of parallel raised portions 22 each of which 75 consists of spaced upwardly convergent side walls 23 and horizontal top walls 24. Each of the raised portions 22 is formed with spaced transverse kerfs 25 constituting burner apertures on the upper face of the burner cap for forming a minor flame zone 80 for generating purposes as will later appear. The burner-cap is designed to contact the central raised portion of the base plate throughout its length to divide the interior of the burner-cap into two longitudinally 85 extending chambers 26 and 27; a dependent rib 28 being formed on the underside of the top wall of the cap adapted to seat on the wall 12. Screws 29 pass through the cap and engage the wall 12 to detachably hold 90 the cap and base plate together.

Seated on the platform 21 is a housing 30 having side walls 31 and 32, end walls 33 and 34, and a top wall 35; the platform 21 forming the bottom wall of the housing. 100 The interior of this housing constitutes an air superheating chamber 36 to which air is admitted from the underside of the base plate through registering openings 37 and 38 in the platform 21 and wall 12 shown in 105 Fig. 5.

Extending parallel with the kerfed raised portions 22 of the burner-cap and spaced thereabove is a pair of generator tubes 39 and 40, the discharge ends of which are fitted with nozzles 41 slidably inserted 110 through openings 42 in the end wall 34 of

the housing 30, and the other ends of which are fitted with threaded tapered nipples 43 adapted to be screwed into threaded openings 44 in a bracket 45 carried on the 5 end wall 18 of the burner-cap. The walls of the openings 44 are formed of brass or other relatively soft metal to insure a non-leakable joint between the bracket and the generators. Nipples 46 are screwed in the 10 outer ends of the openings which are adapted to be connected to any suitable source of hydrocarbon supply through control valves, not shown. The generator tubes contain granular or fibrous material of any suitable 15 character to prevent flooding and also to collect foreign substances and carbonaceous sediment which might be present in the hydrocarbon fuel, thereby largely preventing solid substances from accumulating in the 20 nozzle. As a further means for reducing possibility of clogging of the nozzle, the nozzle tip is formed with an inwardly extending conical end wall 47 through which the nozzle orifice axially extends, the inclined sides of the conical wall tapering from the inner margin of the orifice tending to direct solid particles to the side of the conical extension rather than into the orifice. In event this orifice should become clogged 25 it may be readily freed of obstruction by inserting a fine wire into the orifice from its outer end to press the obstruction back into the nozzle where it will become lodged in the space around the conical extension. The 30 generator tube and nozzle may be cleaned whenever necessary by unscrewing the nozzle from the tube and removing the tube filling. As a means for facilitating cleaning of the nozzle orifice without detaching the 35 generator tube, the housing 30 is formed with a pair of openings 48 in its upper wall through which the cleaning wire may be inserted when it is desired to clean the nozzle. These openings are normally closed by 40 threaded plugs 49.

Extending through the outer end wall of the housing is a pair of intake tubes 50 and 51 arranged in axial alignment with the nozzle orifice with their inner ends spaced a 45 short distance from the nozzles. The outer ends of the intake tubes connect with down turned mixing conduits 52 and 53 the lower ends of which open to the chambers 26 and 27 in the burner cap through the end wall 55 19 of the latter. The intake 50 and 51 are formed with a reduced inside diameter adjacent to their outer ends forming a restricted throat 54 from which the inner walls of the tube taper in opposite directions, a long taper or convergence leading to the throat from the inner end of the tube and a short flare leading from the throat to the outer end of the tube into communication with the conduit. The conduits have 60 an inside diameter greater than that of the 65

intake tubes to permit formation of a partial vacuum at the flared discharge end of the intake tubes and thereby induce a suction in the latter when the burner is in operation. This construction serves to prevent backfire from the burner into the air chamber. 70

In assembling the burner the burner-cap is placed on the base plate and secured thereto by the screws 29. The housing 30 is set on the platform 21 and the generating tubes are put in place by inserting the nozzles into the housing then screwing the tapered nipples into the bracket. The intake tubes 50 and 51 are then inserted through the housing either before or after attachment to the conduits and the mixing conduits are secured thereto by screws 55 and then secured to the burner-cap by screws 56. This construction permits ready removal and replacement of the several parts 80 in event renewal is necessary. 85

From the foregoing it will be seen that I have provided a burner having a pair of separate complementary burner elements 90 formed in one unit and adapted to be operated separately or collectively, each burner element having independent generators, mixing conduits and burner openings with a common air superheating chamber. 95

In the operation of the invention hydrocarbon fuel is delivered to the generator tubes from any suitable source of supply and initial generation is effected in any desired manner as by ignition of a kindling hydrocarbon placed in priming trays 57 formed on the top portion of the burner cap by upturned side flanges 58 from which flames will pass against the generator tube or tubes. These flames act to heat the generator tubes 100 sufficiently to convert the liquid fuel therein into vapors which will be ejected from the nozzles into the enlarged ends of the opposed intake tubes. The jet of vapors entering the convergent throat with considerable 105 force draws air from the air-heating chamber 36 through the restricted throat and carries it into the mixing conduit from whence the air and vapors thoroughly intermingled will be discharged into the burner and pass 110 out the top and side kerfs where the mixture on ignition burns with a hot blue flame. The fresh air drawn into the intake tube is preheated by passing into the chamber 36 the walls of which are heated, which insures 115 a thorough vaporization of the hydrocarbon and its intermixture with air. 120

The flames formed at the top kerfs are impinged on the generator tubes and act to maintain continuous generation of the fuel 125 into vapors. The flames formed at the sides of the burner effect the major heating action and by directing the fuel to either generator the flame may be directed from either side of the burner and where a more intense tem- 130

perature is desired both generators are put in operation.

By forming the burner with dual compartments or chambers and providing means whereby either chamber may be operated independent of the other to form flames on one half of the burner only, pre-ignition of the gases and back firing is prevented as the burner will not be heated sufficiently throughout to cause pre-ignition because the side of the burner not in operation containing an air space will tend to keep down excessive temperature of the other side of the burner. This is advantageous over the ordinary types of hydrocarbon burners for burning kerosene in which flames are emitted throughout the burner head, as excessive heating of the burner and pre-ignition results.

While I have shown and described a specific embodiment of my invention, I do not restrict myself to the exact construction disclosed but may resort to such modifications in the construction and arrangement of parts as are within the spirit and scope of the appended claims without departing therefrom.

I claim:—

1. In a hydrocarbon burner, a rectangular base plate having a longitudinally extending raised central portion comprising spaced side walls and a connecting top wall, a burner-cap seating on said base plate having side, end and top walls with vertical kerfs in its side walls and a pair of rows of transverse kerfs in its top wall, a dependent longitudinally extending rib on the underside of the top wall of said burner-cap between the rows of transverse kerfs seating on the top wall of the raised portion of the base plate and dividing the space within the burner-cap into two compartments, a housing seating on said burner-cap at one end thereof to which air is admitted from the underside of the base plate, a pair of parallel

generator tubes extending over the rows of transverse top kerfs slidably extending into said housing, a pair of intake tubes extending into said housing in alignment with said generator tubes and spaced therefrom and a pair of downturned conduits forming communication between said intake tubes and the two compartments within the cap.

2. In a hydrocarbon burner, a base plate formed with a longitudinally extending raised portion, a burner cap having side walls seating on the edges of said base plate and formed with a top wall adapted to seat on the raised portion of the base plate to divide the interior of the burner cap into two compartments, a series of vertical burner kerfs in the sides of said burner-cap, parallel rows of transverse kerfs on the top portion of the burner cap arranged on opposite sides of the division in the burner cap, and means for delivering hydrocarbon vapors to either or both of said compartments.

3. In a hydrocarbon burner, a pair of complementary burner elements having opposed side burner kerfs and parallel rows of transverse top kerfs, a pair of generator tubes arranged over said top kerfs, a Bunsen tube leading from opposite the discharge end of each of said generator tubes to each burner element and an air heating chamber encircling the adjacent terminals of the generator and Bunsen tubes.

4. In a hydrocarbon burner, a rectangular base, a burner-cap on said base having kerfed corrugated side walls, and a top wall formed with parallel rows of transverse kerfs, a longitudinal partition dividing the interior of the burner-cap between the rows of top kerfs into separate chambers, and means for delivering a mixture of hydrocarbon vapors and air to either or both of said chambers.
